US00D662224S

(12) **United States Design Patent**
Mugge et al.

(10) **Patent No.:** US D662,224 S
(45) **Date of Patent:** ** Jun. 19, 2012

(54) **MOLDED SURFACE OF A CONCRETE PRODUCT**

D21,522 S	5/1892	Lewis

(57) **CLAIM**

The ornamental design for a molded surface of a concrete product, as shown and described.

DESCRIPTION

FIG. 1 is a perspective view of a molded surface of a concrete product showing our new design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines in the drawing views are included for the purpose of illustrating portions of the molded surface of a concrete product that form no part of the claimed design.

1 Claim, 6 Drawing Sheets
